METHOD OF TREATING OILS

David G. Brandt, Westfield, N. J., assignor to
Doherty Research Company, New York, N. Y.,
a corporation of Delaware

Application September 24, 1926, Serial No. 137,411

5 Claims. (Cl. 196—49)

The present invention relates to the cracking of heavier hydrocarbons to obtain lighter hydrocarbons therefrom and more particularly to the treatment of residuums produced during the cracking operation. The invention of the present application is an improvement upon my prior pending application Serial No. 124,320, filed July 23, 1926.

In my prior application I have disclosed a process and apparatus for cracking oils in which residuum is withdrawn from a cracking chamber maintained under a high super-atmospheric pressure, to a distillation chamber or concentrator where the pressure on the residuum is released and the distillation is carried on by the potential heat of the mass. The distillate recovered in this operation is pumped into a mixing chamber into which is also charged raw oil and reflux condensate from a reflux tower, the mixture being pumped to a heater where it is heated to the cracking temperature.

The important objects of the present invention are improvements in the process and apparatus for treating the residuum withdrawn from the cracking chamber by carrying out the distillation thereof without releasing the pressure; to avoid loss of heat due to the reduction in the pressure on the residuum and to return the resulting distillate to the cracking chamber solely by its own pressure head.

The novel features of the present invention are pointed out with particularity in the appended claims. The invention itself, however, together with further objects and advantages will be best understood from the following description taken in connection with the accompanying drawing in which:—

The figure is an elevational view, partly in section and diagrammatic in character, of an apparatus adapted to operate in accordance with the process of the present invention and including the novel features hereinafter described and claimed.

As illustrated in the drawing raw charging stock, preferably gas oil first enters the system through pipe 2 and is forced by feed pump 4 through pipes 6 and 8 to the upper part of a tower 10 which functions as a heat exchanger, a bubble tower and a dephlegmator. The pipe 8 connects with a series of coils or heat exchangers 12 positioned above and between the various trays 14 in the column 10 as described in detail in the pending application referred to. The oil pre-heated in the exchangers 12 discharges onto the

lowermost tray from which it flows with reflux condensate collected from the trays above.

The dephlegmating tower 10 is preferably set on or made integral with a cracking chamber 16, in which a frusto-conical plate 18 serves as a separating partition between the two chambers. The plate 18 has a central aperture 20 through which reflux condensate and charging stock discharge from the tower 10 into the chamber below.

The cracking chamber 16 is preferably divided by a diaphragm 22 into an upper cracking chamber proper and a lower mixing chamber 24. Connecting with the mixing chamber 24 and mounted on the diaphragm 22 is a conduit 26 which extends up through the cracking chamber to within a short distance of the aperture 20 in the plate 18. Conduit 26 preferably carries a funnel-shaped mouth 28 at its upper end for receiving the reflux and charging stock discharging through the opening 20. This construction of the conduit 26 and mixing chamber prevents the direct mixing of the charging stock and reflux condensate with the oil undergoing cracking in the cracking chamber. Material which has undergone cracking in the cracking chamber may pass from the lower end of this chamber into the mixing chamber 24 by the pipes 30 where it mixes with the charging stock and reflux condensate from the tower 10. This mixture, which may have any desired proportion of the various constituents, is withdrawn from the mixing chamber by valved conduit 32 and pump 34 and forced under considerable pressure through pipe 36 to the tubular heating furnace 38 where the oil is raised to a suitable cracking temperature. The highly heated oil is conducted from the heating furnace by valved conduit 40 to the upper end of a separating chamber 42 where vapors are permitted to separate from unvaporized oil.

The separator 42 preferably comprises a means such as the funnel-like partition conduit 44 for delivering the unvaporized oil, entering the top of the chamber, to the bottom thereof so that the oil leaving the separator near the top by the conduit 46 must first go to the bottom of the chamber and rise around the conduit 44, thus leaving any carbon or sludge constituent in the bottom of the chamber. The conduit 46 connects the separator directly with the cracking chamber 16 in which the oil gradually works its way downward and into the mixing chamber 24 or as explained later may be drawn directly into a concentrator 52 for treatment. Vapors from separator 42 pass by conduit 48 into the cracking chamber and are distributed into the oil therein.

by means of the distributor 50 which is placed directly above the pipes 30.

Since considerable time is required for the cracking operation to complete itself the chambers 42 and 16 are preferably constructed sufficiently large to give ample time for the cracking step. It will be clear from the description given that any oil which is about to crack and which is nearing the outlet pipes 30 will receive the maximum effect of the high temperature vapors leaving the distributor 50 and will be cracked thereby, thus minimizing the amount of cracking which will occur beyond this point or in the heater 38.

15 In the construction shown the residuum formed in the various chambers is treated in the concentrator 52. For this purpose valved branch pipes 54 and 56 connect the separator 42 with a main discharge line 58 leading to the concentrator 20 52. Similarly a valved pipe 60 connects the lower portion of the mixing chamber 24 with the pipe 58 and a valved pipe 62 connects the lower part of the cracking chamber proper with the pipe 58.

The concentrator is preferably divided by an inverted funnel-like partition 64 into a lower vaporizing chamber 66 and an upper dephlegmating and condensing chamber 68, and is preferably positioned with respect to the separating and cracking chambers so that the residuum 30 will flow by gravity into and fill the part 66 to about the proportion shown in the drawing. The level of the liquid in the three chambers (42, 16 and 52) should be maintained substantially as shown, by proper regulation of the oil fed to and 35 withdrawn from the system.

The residuum introduced into the concentrator is maintained under the same pressure as is maintained on the oil in the cracking chamber, which may range from atmospheric to several 40 hundred pounds per square inch; ordinarily between 100 and 300 pounds. In the vaporizing chamber 66 the vaporization of the more volatile constituents including the gas oil is effected by introducing a gas through the distributor 70 45 mounted in the lower part of the chamber 66. The gas leaving the distributor passes upward around the baffles 72, carrying with it vapors of the residuum and enters the dephlegmating and condensing chamber 68 through the partition 64. 50 In this chamber the gas and vapor pass counter-current to a flow of reflux condensate and finally contact the water-cooled condenser 74 in the upper part of the chamber, which condenses out the lower boiling vapors. The condensate thus 55 formed passes by its own pressure head through the liquid sealed conduit 75 directly into the conduit 26 within the cracking chamber then into mixing chamber 24 where it mingles with the oil therein. The non-condensed gas leaves the concentrator by valved conduit 76 and is recirculated 60 through the system by the pump 78 and pipe 80 which connects with the distributor 70. The conduit 80 is formed into a coil in heat inter-changer 82 which receives the hot residuum 65 discharged from the concentrator by the valved pipe 84, thereby providing a means for extracting the heat from the residuum before its final discharge from the system. The cooled residuum 70 stripped of its lighter fractions is discharged from the interchanger 82 by the valved conduit 86 to be used as fuel oil. The gas to be used in the circuit including the concentrator 52 may be introduced through valved pipe 88 from any suitable 75 source but ordinarily it is taken from the non-

condensed gases leaving the final condenser of the cracking system. Due to the absorption of the gas in the cooler oil in chamber 68, it may be necessary from time to time to introduce make-up gas through the pipe 88.

5 Connecting with the oil inlet pipe 8 is a valved pipe 90 through which charging stock may be admitted directly to the conduit 26 without passing it through the dephlegmator coils. By manual or automatic adjustment of the valves in conduits 10 8 and 90 the temperature in the dephlegmator 10 may be regulated in accordance with the boiling point desired for the vapor leaving the dephlegmator. The vapors not condensed in the tower 10 pass by valved vapor line 92 to a water-cooled condenser 94 from which the condensate and non-condensed gases pass by pipe 96 to suitable traps and containers (not shown) all of which are common in the art.

15 In operating the apparatus described, in accordance with the present invention the oil residue either from the separator 42, the mixing chamber 24, the cracking chamber proper or all of them is conveyed by conduit 58 into the concentrator 52 where it is maintained under the 25 pressure existing in the chambers mentioned. Gas is introduced through the pipe 88 and forced through the pipe 80, distributor 70 and upward through the body of residuum as it flows slowly down over the baffles in the chamber 66. While 30 the physical pressure in chambers 16 and 66 is substantially the same the presence of the gas in the latter has the effect of reducing the pressure on the residuum by producing therein a partial pressure of the vapors of the residuum and thereby causes the vaporization of the lighter fractions thereof. In this operation the gas may be supplied at a high velocity and in large quantities to sweep out the lighter ends of said residuum or it may be used in smaller amount and at a 40 slower velocity but heated to a higher temperature for carrying out the distillation. With either procedure the gas is constantly circulated in the system so that none of the vaporized oil is taken therefrom. The vapors carried by the gas from chamber 66 are condensed in chamber 68 and returned to the mixing chamber 24 while the gas is constantly recirculated through the residuum by pump 78 as referred to above.

45 An important feature of the present invention is the prevention of the deposition of carbon in the various chambers and conduits by constantly (either intermittently or continuously) circulating a large amount of oil through the separator, cracking chamber, concentrator and heater and 50 constantly removing any carbon and sludge formed in these chambers with the fuel oil discharged from the vaporizing chamber 66 of the concentrator.

55 In order to prevent the building up of a pressure in the concentrator greater than that in the other chambers and thus stop the flow of residuum therefrom I have provided a pressure equalizing line 98 between the concentrator 52 and the tower 10. A check valve 100 is provided in this line to prevent flow from the tower to the concentrator but allow flow in the opposite direction. Ordinarily the pressure in the concentrator is kept substantially the same as that in the chamber 16 by the proper regulation of the valve in pipe 76, the suction and force of pump 78 and the amount of gas introduced through the pipe 88, but in case of a sudden increase in pressure in the concentrator the line 98 will act as a relief.

70 The concentrator, dephlegmator, cracking 75

chamber, and separator are heat-insulated as shown by the legends in the drawing. The conduits carrying hot oil, etc., are also preferably heat-insulated but for simplicity such showing is 5 omitted.

I claim:

1. The process of cracking petroleum oils, which comprises passing oil from a hot oil chamber through a heating zone and then into an enlarged reaction chamber, maintaining a super-atmospheric pressure on the oil undergoing cracking in said reaction chamber, passing vapors from said reaction chamber into a reflux tower in heat exchange with fresh charging stock for the process, passing fresh charging stock and reflux condensate from said tower into said hot oil chamber, withdrawing residuum from said reaction chamber into a concentrator, maintaining the withdrawn residuum under substantially the same pressure as that in said reaction chamber, passing a preheated gas through said withdrawn residuum to effect vaporization of substantial portions thereof by the partial pressure effect of said gas, condensing the resulting vapors, and passing the condensate produced therefrom into said hot oil chamber.
2. In the process of cracking oils under super-atmospheric pressure in which the oil is passed through a heating zone and into a cracking chamber, the improvement which comprises withdrawing vapors from said chamber, passing said vapors through refluxing and final condensing stages and separately withdrawing residuum from said chamber into a concentrating still upon the completion of the desired cracking thereof, effecting distillation of substantial portions of said withdrawn residuum in said still by introducing a gas thereinto in intimate contact with said residuum, without further subjecting the residuum to cracking conditions and while maintained under substantially the same pressure as the pressure maintained on the oil in said chamber, subjecting the vapors evolved from said residuum to reflux condensing conditions in a reflux condensation zone while maintained under substantially the same pressure as the pressure maintained on the oil in said chamber, subjecting the vapors evolved from said residuum to the oil to be passed through 40 the said heating zone.
3. The process of cracking petroleum oils, which comprises passing oil from a hot oil sup-

ply chamber through a heating zone in which the oil is heated to a cracking temperature and then into an enlarged chamber, maintaining a super-atmospheric pressure on the oil in said zone and chamber, maintaining a pressure in said supply chamber substantially equal to that maintained in said enlarged chamber, passing vapors from said enlarged chamber and subjecting them to fractional condensation, withdrawing residuum from said enlarged chamber into a concentrator, 10 maintaining the withdrawn residuum in said concentrator under substantially the same pressure as that maintained in said enlarged chamber, passing a gas in intimate contact with the residuum in said concentrator to thereby effect vaporization of substantial portions thereof by the partial pressure effect of said gas, condensing the higher boiling point portions of the resulting vapors suitable as cracking stock, and passing the resulting condensate by gravity into said supply 20 chamber.

4. In the process of cracking oils under super-atmospheric pressure in which the oil is passed through a heating zone and into a cracking chamber, the improvement which comprises withdrawing vapors from said chamber for condensation and separately withdrawing residuum from said chamber into a concentrating still, effecting distillation of substantial portions of said withdrawn residuum in said still without further subjecting 30 the residuum to cracking conditions and while maintained under substantially the same pressure as the pressure maintained on the oil in said chamber, subjecting the vapors evolved from said residuum to reflux condensing conditions in a 35 reflux condensation zone while under said pressure to produce therefrom a distillate suitable for re-cracking, effecting the distillation of said withdrawn residuum in said still by passing a gas in a closed cycle through the residuum in said concentrating still and through the reflux condensation zone, and adding the said distillate produced from said residuum to the oil to be passed 40 through said heating zone.

5. The process defined by claim 4 in which unvaporized oil residue is withdrawn from said concentrating still, and preheating the gas introduced into said concentrating still by passing it in indirect heat exchange with said withdrawn unvaporized oil residue.

DAVID G. BRANDT.
